W. R. TURNER

ROLL PAPER PASTING MACHINE

Filed March 13, 1922

witness:

R. H. Hamilton

INVENTOR
William Ralph Turner
BY
Warren O. House
His ATTORNEY

UNITED STATES PATENT OFFICE.

WILLIAM RALPH TURNER, OF KANSAS CITY, MISSOURI.

ROLL-PAPER-PASTING MACHINE.

Application filed March 13, 1922. Serial No. 543,138.

To all whom it may concern:

Be it known that I, WILLIAM RALPH TURNER, a citizen of the United States, residing at Kansas City, in the county of Jackson and State of Missouri, have invented a certain new and useful Improvement in Roll-Paper-Pasting Machines, of which the following is a specification.

My invention relates to improvements in roll paper pasting machines.

One of the objects of my invention is to provide novel means for applying paste to the upper side of a strip of paper drawn horizontally off from a paper roll, such as

a roll of wall paper.

A further object of my invention is the provision of pasting means of the kind described which is simple, cheap to manufacture, durable, not liable to get out of order, which can be efficiently operated by an unskilled person and which may be conveniently used in connection with an ordinary pasting board.

A further object of my invention is to provide novel means by which paper drawn from a roll may be accurately measured and positioned for severing into strips of desired length.

My invention provides still further a novel paper supporting table provided with a cutting groove in its upper surface arranged to co-operate with graduations on a pasting board.

My invention provides further a table having novel means for supporting and holding from lateral movement one end of a pasting board.

My invention provides still further novel means for supporting a roll of paper in contact with a pasting roller arranged so that when paper is withdrawn from the roll, the latter will be pressed against an adjacent pasting roller.

The novel features of my invention are hereinafter fully described and claimed.

In the accompanying drawing, which illustrates the preferred embodiment of my invention,

Fig. 1 is a side elevation, partly broken away, of my improved pasting machine, shown supporting one end of a pasting board.

Fig. 2 is a top view of the same,

Fig. 3 is a vertical sectional view on the line 3—3 of Fig. 2.

Fig. 4 is a vertical sectional view on the broken line 4—4 of Fig. 1.

Similar reference characters designate similar parts in the different views.

1 designates a paste receptacle, which as shown, is a rectangular box in which is rotatably mounted on a horizontal axis a pasting roller 2, which extends into the paste 3, and which is provided with a central horizontal shaft 4, having projecting ends 5, mounted in vertical recesses 6, Fig. 4, provided in the upper ends of two blocks 6, secured respectively to the inner sides of the end walls of the receptacle 1.

Two upright members 7 comprising two legs of a table are secured at their lower ends to opposite ends respectively of the receptacle 1. To the upper ends of the legs 7 is secured a table top 8, which is also supported at its under side by two brackets 9, respectively secured to the legs 7 and which extend to the left, as viewed in Figs. 1 to 3, of the adjacent edge of the table top 8, and which are adapted to support one end of an ordinary pasting board 10, which may be provided on its under side with two vertical holes adapted to respectively receive two vertical pins 11, which extend upwardly from the projecting portions of the brackets 9, and which hold the board 10 from lateral or horizontal movement. The other end of the board 10 may be supported in any suitable manner by means not shown.

The upper side of the table top 8 is provided with a transverse groove 12, at right angles to the board 10, and arranged to serve as the zero mark in co-operation with a longitudinal row of graduations 13, with which the upper side of the board 10 may be provided, as shown in Fig. 2. The groove 12 is adapted to receive a knife blade, not shown, which may be used for severing a strip of paper 14, which may be drawn from a roll of paper 15, across the groove 12, and longitudinally along the pasting board 10.

For supporting the paper roll 15, there is provided a swinging frame comprising, preferably, two bars 16, pivoted intermediate of their ends on a horizontal axis parallel with the shaft 4, and which may comprise two pins 17, which extend through the bars 16 respectively and are mounted in the legs 7.

The paper roll 15 is, as usual, provided

with a central longitudinal hole in which are adapted to be fitted conical blocks 18, Fig. 4, through which extends a horizontal removable rod 19, which has its ends removably fitted in the bars 16 at one side of the axis thereof.

The frame is provided at its upper end and at the other side of the axis thereof with paper bearing means comprising preferably 10 a roller 20, secured on a horizontal rod 21, having projecting ends which are preferably loosely rotatably mounted in the bars 16 respectively.

In the operation of my invention, the paper 15 is drawn from the roll 15, over and against the roller 20, and against the pasting roller 2, and over the groove 12, and onto the pasting board 10, to the graduation of the row 13, which indicates the length of 20 strip desired to be severed. A suitable knife blade is then drawn through the groove 12, and through the overlying strip of paper 14, thus severing the strip.

When the strip of paper 14 is drawn along 25 the top of the pasting board 10, in the manner just described, the pressure of the paper against the roller 20 will press the bars 16 so as to hold the periphery of the roll of paper 15 tightly against the paste covered 30 periphery of the pasting roller 2.

What I claim is:—

1. In a roll paper pasting machine, a paste receptacle, a pasting roller rotatable in said receptacle, a table having a top and two legs, the latter being attached to opposite sides respectively of said receptacle and the top having in its upper side a groove adapted 35 to receive a cutting knife, and a paper roll supporting frame pivoted to the legs of the table and having a roller adjacent to its upper end, and provided adjacent to its lower end with means for supporting a paper roll in contact with the periphery of the pasting roller, the axes of said rollers and said groove being parallel with each other, the arrangement being such that when the paper from the roll is drawn over the frame roller and said groove, the frame will hold 40 the paper roll against said pasting roller, substantially as set forth.

2. In a roll paper pasting machine, a paste receptacle, a pasting roller rotatable thereon on a horizontal axis, a table having a top and provided with two legs supported 55 by said receptacle, the table having means for attaching and supporting one end of a pasting board, and a frame pivoted to said table between said legs and having means at one side of its axis for supporting a roll of 60 paper and for holding the latter against said pasting roller and having at the other side of its axis bearing means parallel with said roller and disposed at the side of the table opposite said attaching and supporting means, substantially as set forth.

3. In a roll paper pasting machine, a paste receptacle, a pasting roller rotatable therein on a horizontal axis, a table having two legs attached to and supported by said receptacle and having a top and provided with two brackets respectively secured to said legs and supporting said top and extending laterally from the latter and provided with means for supporting and holding from lateral movement one end of a pasting board, and means for supporting a paper roll, and for forcing the latter against the pasting roller, when paper is withdrawn from the roll and over the top of the table between said brackets, substantially as set 80 forth.

4. In a roll paper pasting machine, a table having two supporting legs and a top and provided with two brackets respectively attached to said legs and to the bottom of said table top and projecting beyond one edge of the latter, the brackets having means for supporting and holding from lateral movement one end of a pasting board, the top of the table having a transverse groove adapted to receive a cutting knife, means for supporting a paper roll, and means for applying paste to one side of the paper when the paper is withdrawn from the roll across said groove, substantially as 95 set forth.

5. In a roll paper pasting machine, a table having two supporting legs and a top having in its upper side a transverse groove adapted to receive a knife blade, the table having two brackets attached to the under side thereof and extending beyond one edge thereof, each bracket having an upwardly extending pin adapted to enter a hole in a pasting board, the brackets being adapted 100 to support one end of the pasting board, means for supporting a paper roll, and means for applying paste to one side thereof when the paper is drawn from the roll across said groove, substantially as set forth. 110

6. In a roll paper pasting machine, a paste receptacle, a pasting roller rotatably mounted therein, two members extending upwardly from the receptacle at opposite ends respectively of said roller, two bars pivoted on a horizontal axis on said members, said axis and the axis of said roller being parallel, means for supporting a paper roll on said bars at one side of the axis thereof and in a position in which the bars 115 may be swung so as to bring the roll of paper against the periphery of said roller, and a roller rotatably mounted on said bars at the opposite side of the axis thereof and parallel with the other roller, and adapted 120 to serve as a bearing for paper withdrawn from the roll and when so functioning serving to press the bars so as to hold the paper roll against the pasting roller, substantially as set forth. 125

7. In a roll paper pasting machine, a table having a top provided in its upper side with a transverse groove adapted to receive a knife blade, the table having means for supporting one end of a pasting board with the upper side thereof in the same plane substantially as the upper side of the top of the table, and a pasting board having graduations arranged in a longitudinal row and co-operating with said groove, for measuring paper drawn across said groove and onto said pasting board, substantially as set forth.

8. In a roll paper pasting machine, a table having a top provided in its upper side with a transverse groove adapted to receive a knife blade, the table having means for supporting one end of a pasting board disposed at right angles to said groove, and a pasting board having a longitudinal row of graduations co-operating with said groove for measuring paper drawn over said groove and onto said pasting board, and means by which paste is applied to the side of said paper which constitutes the upper side, as the paper is drawn across said groove, substantially as set forth.

9. In a roll paper pasting machine, the combination with a pasting board having a longitudinal row of graduations, of a table having a top and two legs, the upper side of the top having a groove at right angles to said row of graduations and cooperating therewith to serve as a scale for measuring paper drawn across said groove onto said pasting board, the table having means for supporting one end of said board in the

proper measuring position, a paste receptacle, a pasting roller rotatable on a horizontal axis in said receptacle, and a frame pivoted to said legs on an axis parallel with the roller axis, said frame having means at one side of the axis thereof for supporting a paper roll, and provided at the other side of the axis thereof with bearing means over which paper withdrawn from the roll is drawn, the arrangement being such that paper drawn from the roll and on said bearing means and across said groove will press said frame so as to hold the paper roll against the periphery of the pasting roller, substantially as set forth.

10. In a roll paper pasting machine, the combination with a paste receptacle, of a pasting roller rotatable on a horizontal axis in said receptacle, two members extending upwardly from said receptacle at opposite ends respectively of said roller, and a frame pivoted at opposite sides to said members respectively on an axis parallel with the axis of said roller and having means at one side of the axis thereof for supporting a paper roll in contact with said roller, and at the other side of the axis thereof having paper bearing means arranged to hold said frame so as to press the paper roll against the pasting roller when paper from the roll is drawn therefrom and over said bearing means and across the axis of said frame, substantially as set forth.

In testimony whereof I have signed my name to this specification.

WILLIAM RALPH TURNER.
